UNITED STATES PATENT OFFICE.

CHARLES WEISS, OF NEW YORK, N. Y.

DESIGN FOR A PLATE OR SIMILAR ARTICLE.

Application filed March 3, 1925. Serial No. 12,558. Term of patent 7 years.

To all whom it may concern:

Be it known that I, CHARLES WEISS, a citizen of the United States, residing at New York city, in the county of New York and State of New York, have invented a new, original, and ornamental Design for Plate or Similar Article, of which the following is a specification, reference being had to the accompanying drawing, forming part thereof.

The figure is a plan view of a plate showing my design.

The ornamental border illustrated is to be repeated throughout the entire circumference of the border.

I claim.

The ornamental design for a plate or similar article, as shown.

CHARLES WEISS.
